UNITED STATES PATENT OFFICE

GUY R. DE VALL, OF NEW YORK, N. Y.

DESIGN FOR A RADIATOR-CAP ORNAMENT OR SIMILAR ARTICLE

Application filed April 22, 1930. Serial No. 35,342. Term of patent 3½ years.

To all whom it may concern:

Be it known that I, GUY R. DE VALL, a citizen of Great Britain, and a resident of the city of New York, borough of Manhattan, in the county of New York and State of New York, have invented the new, original, and ornamental Design for a Radiator-Cap Ornament or Similar Article, of which the following is a specification.

Reference is to be had to the accompany-

ing drawing forming a part thereof, in which Figure 1 is a front view of a radiator cap ornament or similar article, showing my new design;

Figure 2 is a plan view.

I claim:

The ornamental design for a radiator cap ornament or similar article, substantially as shown.

GUY R. DE VALL.
